US0D1065568S

(12) **United States Design Patent** (10) Patent No.: **US D1,065,568 S**
(45) Date of Patent: ** Mar. 4, 2025

(54) **SCRAPING MASSAGE TOOL**

(71) Applicant: **Hongbo Wang**, Langzhong (CN)

(72) Inventor: **Hongbo Wang**, Sichuan (CN)

(73) Assignee: **Hongbo Wang** (CN)

(**) Term: **15 Years**

(21) Appl. No.: **29/892,774**

(22) Filed: **May 22, 2023**

(51) LOC (15) Cl. **24-01**

(52) U.S. Cl.

USPC **D24/215**

(58) **Field of Classification Search**

USPC D24/133, 146, 200, 211, 212, 213, 214,

D24/215

CPC A61H 15/0092; A61H 2201/169; A61H 7/00; A61H 7/003
